UNITED STATES PATENT OFFICE.

HERMAN F. NEHR, OF SHELTON, CONNECTICUT, ASSIGNOR TO LOUIS HAAS, OF NEW YORK, N. Y.

DESIGN FOR AN ADVERTISING SIGN-CASE.

SPECIFICATION forming part of Design No. 25,359, dated April 7, 1896.

Application filed February 17, 1896. Serial No. 579,867. Term of patent 7 years.

To all whom it may concern:

Be it known that I, HERMAN F. NEHR, a citizen of the United States, residing at the city of Shelton, county of Fairfield, and State of Connecticut, have invented and produced a new and original Design for Advertising Sign-Cases, of which the following is a specification.

The essential feature of my design resides in the configuration of the casing, substantially as shown in the accompanying drawing, which shows the casing in perspective.

The casing is rectangular in general aspect, and has a rectangular aperture 2 in front. On the front are two rectangular plates 3 4, within which is a vertical slot 5.

Extending diagonally from the front edges

of the case are L-shaped brackets 6, as shown, they having divergent ears 7 overlapping the corners of the case. The ears are configured on their upper edges, each having the enlargements or projections 8, the lower edges being flush with the bottom of the casing.

Having described my invention, I claim—

The design for an advertising sign-case, substantially as herein shown and described.

Signed at the city of Shelton, county of Fairfield, State of Connecticut, this 13th day of February, 1896.

HERMAN F. NEHR.
